Inventor:
Burt W. Decatur,
By Harry W. Brown.
Atty.

UNITED STATES PATENT OFFICE.

BURT W. DECATUR, OF SPRINGFIELD, MASSACHUSETTS.

AXLE-SETTING TOOL.

Application filed October 6, 1917. Serial No. 195,137.

To all whom it may concern:

Be it known that I, BURT W. DECATUR, a citizen of the United States, residing at Springfield, in the county of Hampden and 5 State of Massachusetts, have invented new and useful Improvements in Axle-Setting Tools, of which the following is a specification.

The object of this invention is to provide 10 means for testing axles of automobiles to see whether or not they are true and to determine the amount of bend to be given the axle to straighten it if it is not true.

Another object of the invention is to provide 15 means which may be connected with the spindle body of an automobile so that a compass may be used to see whether or not the spindle has the proper set.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying 30 drawings wherein like characters denote like or corresponding parts throughout the several views, and in which:—

Figure 1 is a plan view of the invention in use.

Figure 2 is a side view thereof.

Figure 3 is a section on the line 3—3 of 35 Figure 1.

Figure 4 is a section on line 4—4 of Figure 1.

Figure 5 is a view of means for gaging the spindle.

Figure 6 is a section on line 6—6 of Figure 4.

Figure 7 is a perspective view of the U-shaped supporting member and one of its cones.

Figure 8 is a sectional view showing the means for clamping the rod 25 to its supporting post 24.

Figures 9 and 10 are diagrammatic views illustrating how the invention is used.

In carrying out my invention I may utilize any kind of a bending device but I prefer to use a stationary vise and a movable vise for engaging the axle and bending the same. In the figures, 1 indicates the stationary vise located on the work-bench 2.

This vise consists of the stationary jaw 3

and the movable jaw 4 which is actuated by the handle 5. 6 represents the movable vise which consists of the stationary jaw 7 and the movable jaw 8 operated by the handle 9 which is pivoted to the usual screw carried by the jaw and engaging a stationary part of the vise. The stationary jaw 7 is provided with an extension 10 for receiving the movable jaw and the device as a whole is 60 adapted to slide on a plate 11 located on the bench. The means for moving said vise consists of a screw 12 engaging a hole 13 in the vise and a collar 14 connected with said screw is provided with a lug 15 which is 65 adapted to engage with any one of a series of holes 16 in the plate 17 secured to the bench. By this means the movable vise may be adjusted as to its distance from the stationary vise. The extended end of the screw 70 12 is provided with a hand wheel 18 by which said screw may be rotated to move the vise at right angles to the longitudinal plate 11. After the axle is placed in position in the vises I first test the same to discover the 75 amount of bend to be given thereto to straighten the same and such means constitutes my invention.

In carrying out my invention I pass a rod 19 through the holes in one of the forked ends of the axle and I center said rod therein by means of a pair of cone members 20 having holes therein through which the rod passes. Thumb screws 21 hold the cone members on the rod. Said rod 19 is provided 85 with punch marks *a* and *a'* adjacent its ends and one end of this rod carries a scale 19' which is secured to a sleeve 19^x which is 90 adjustably mounted on said rod by means of the screw 19^a. I provide a right angular projection 19'' on the rod which engages a slot 23' in one of the cones 20, as shown in Figure 4. This projection is located an equal 95 distance from the punch marks *a* and *a'* and acts as a means for properly positioning the 100 rod in the forked end of the axle so that the punch marks will be an equal distance from that part of the axle which is in engagement with the stop or projection 19''. When the 105 holes in the axles are of large size and the cones 20 are too small to be supported in the axles I may provide grooves 23^x in the cones and place rods 23^a in engagement with said grooves so that said rods will space the cones from the inner walls of the holes, as 110 shown in Figure 6.

At the other end of the axle I locate a

U-shaped rod 22 which has one limb thereof passing through the holes in this end of the axle and centered therein by the cone members 23 which are similar to those just described. The U-shaped member is provided with an extension 22' which receives one of the cones 23, this cone being provided with a slot 23' through which the cross member of the U-shaped member passes, as clearly shown in Figures 1 and 7. At the junction of the free limb of the U-shaped member with the cross piece thereof, is located a punch hole *b*. This punch mark *b* is adapted to be in the same plane with the lowermost surfaces of the forked ends of the axle as viewed in Fig. 1 and also with the stop 19 when the axle is straight. This free limb of the U-shaped member engages the upper side of the axle, as shown in Figure 1. The gaging device consists of the upright post 24 which has its pointed end adapted to engage the punch mark *b*, and the measuring bar 25. The post carries a bolt 26 which is adapted to be clamped to the post by the nut 26' and said bolt has a slotted head in which is slidably mounted the bar 25, the bar being held in adjusted position in the head by the set screw 26''. This arrangement of parts permits the bar 25 to be adjusted longitudinally and it can also be adjusted angularly to the post. The post is provided with a scale 24' which cooperates with the bar 25 to indicate the angular adjustment. The end of the bar 25 carries a point 27 which extends at right angles from the bar and a second point 28 is adjustably secured to the bar by means of the thumb screw 29. These points cooperate with the scale 19' carried by the rod 19. After the axle is placed in the vises, the rods 19 and 22 are properly positioned in the forked ends of the axle by means of the cones, the stop 19'' and the bight of the U-shaped rod 22. The stop 19'' and the bight of the U-shaped rod engaging the axle will act as positioning means for the rods and if the axle is straight the punch mark *b* the lowermost surfaces of the forks of the axle and the stop 19'' will be in the same plane and therefore the punch marks *a* and *a'* will be equal distances from the punch mark *b*. The fact whether or not these distances are equal can be determined by the measuring bar 25 by placing the pointed end of post 24 in punch mark *b* and then adjusting the rod 25 to make its point 27 engage the punch mark *a'*, as shown in dotted lines in Figure 1. The bar 25 is then moved to its full line position and if it engages the punch mark *a*, the punch marks *a* and *a'* are the same distances from the punch mark *b*, thus showing that the rod 19 is parallel with the rod 22 and that the axle is straight. This is shown in Figure 9 wherein the triangular lines *b*—*c*—*a*

are of the same dimensions as the triangular lines *b*—*c*—*a'*. If the axle is not straight the stop or projection 19'' will not be in the same plane with the said surfaces of the forks with the mark *b* and the punch mark *a* will be closer to or farther from the mark *b* than the mark *a'* is from said mark *b*. This is shown in Figure 10 where the line *b*—*a* is longer than the line *b*—*a'*. The measuring bar and scale 19' will show the difference in the length of the two lines. When the axle is being straightened one end of the rod 19 will move inwardly while the other is moving outwardly so that it is only necessary to bend the axle sufficiently to move the rod half the distance indicated by the scale and in order to determine when a sufficient amount of bend has been given the axle bar 25 is adjusted on scale 24' to the mark which indicates one half of the amount that line *b*—*a* varies from line *b*—*a'*, and which is shown by scale 19'. This movement of the rod 25 will move point 27 the proper distance away from or towards mark *b* to indicate the amount of bend necessary to be given the axle. Then when the axle has been bent sufficiently to permit the point 27 to engage both the marks *a* and *a'* the axle will be straight. For instance, if the scale 19' indicated that the line *b*—*a* was longer by twenty degrees than the line *b*—*a'* the bar 25 would be adjusted on the scale 24' ten degrees, then the axle would be bent until the mark *a* could be engaged by the point 27.

I may use the rod 19 for testing the true-ness of the spindle of the front wheel of an automobile. This may be done by placing the sleeve carrying the spindle on the rod 19 and centering it by means of the cone members. Collars 30 are then placed on the rod and located an equal distance from the center of the spindle sleeve. This may be done by placing one point of a compass at the point *c* at the middle of said sleeve and placing the collars at the intersection of the curved line *c'*, made by said compass, with the rod 19. Then by measuring the distance between the collars and the outer end of the spindle, as shown by the lines *c''*, the amount of "set" of the spindle can be determined.

Instead of using the scale 24' I may use the point 28. This point 28 is set on rod 25 a distance from point 27 that is equal to half the distance line *b*—*a* varies from line *b*—*a'*, as shown by scale 19'. When the axle is straightened this point 28 will touch both punch marks and thus prove that the axle is straight.

What I claim is:—

1. A gaging device comprising a rod provided with measuring points, cones for centering the rod in the part to be gaged with the said measuring points equidistant from

the selected point on the part to be gaged, and a measuring bar for gaging the distance between the said points.

2. A gaging device for automobile axles comprising a pair of rods, means for centering said rods in the spindle bolt holes of an axle, means for holding each rod in a certain position relative to the axle, a measuring bar supported by one rod and 10 the other rod being provided with measuring points arranged equidistant from the positioning means of the rod to be engaged by the said measuring bar.

3. A gaging device for automobile axles comprising a pair of rods, means for centering said rods in the spindle bolt holes of an axle, stop means for holding each rod in a certain position relative to the axle, an adjustable measuring bar supported by 15 one rod and means on the other rod, arranged equidistant from the positioning means on said rod for providing measuring points for the said bar.

4. A gaging device for automobile axles comprising a pair of rods, cones for centering said rods in the spindle bolt holes of an axle, stop means for holding each rod in a certain position relative to the axle, a measuring bar supported by one rod, 20 measuring points on the other rod, arranged equidistant from the stop means on said rod for providing measuring points for the measuring bar and a scale arranged on the rod adjacent one of the measuring points.

35 5. A gaging device for automobile axles comprising a pair of rods, cones for centering said rods in the spindle bolt holes

of the axle, a stop on each rod for holding the same in a certain position relative to the axle, a measuring bar supported by one 40 rod, and being adjustable in the arc of a circle, a scale for indicating the amount of this adjustment, the other rod having measuring points thereon, arranged equidistant from the stop on said rod, for providing measuring points for the measuring bar and a scale on said rod adjacent one of 45 said points.

6. A gaging device for automobile axles comprising a straight rod and a U-shaped 50 rod, cones on said rods for centering them in the spindle bolt holes of the axle, a stop on the straight rod for engaging the axle, the crosspiece of the U-shaped rod acting as a stop for this rod, the said U-shaped 55 rod having a punch mark *b* thereon which is adapted to be in the same plane with the lowermost surfaces of the forked ends of the axle and also with the stops of the said straight and U shaped rods when the axle 60 is straight, the straight rod having a pair of punch marks thereon, arranged equidistant from the stop thereon, a post having a pointed end for engagement with the punch mark *b*, a measuring bar pivotally 65 connected with the post, a scale on the post for indicating the amount of movement of the bar, said bar being mounted for adjustment in the arc of a circle, a point on the bar for engaging the punch marks on the 70 straight rod and a scale on said straight rod located adjacent one of the punch marks.

In testimony whereof I affix my signature.
BURT W. DECATUR.
